Primary Examiner — Richard E Chilcot(74) *Attorney, Agent, or Firm* — Volpe Koenig(57) **CLAIM**

The ornamental design for a faucet stream straightener, as shown and described.

DESCRIPTION

FIG. 1 is a top plan view of a faucet stream straightener in accordance with my design;

FIG. 2 is a top, front perspective view thereof;

FIG. 3 is a bottom plan view thereof;

FIG. 4 is a bottom, rear perspective view thereof;

FIG. 5 is a front elevational view thereof;

FIG. 6 is a left side elevational view thereof;

FIG. 7 is a rear elevational view thereof; and,

FIG. 8 is a right side elevational view thereof.

The broken lines represent portions of the faucet stream straightener in which the design is embodied that form no part of the claimed design.

1 Claim, 4 Drawing Sheets(56)
